STRIPPER FINGERS FOR FLAT WORK
IRONERS

Charles Edwin Hamilton, Sr., Hollywood, Calif.,
assignor to Edwin Lane, Percy Mendelson, and
Charles Mendelson, all of New York, N. Y.

Application March 28, 1931, Serial No. 525,896

8 Claims. (Cl. 68—9)

The invention relates to laundry and dry cleaner machinery, more especially to the so-called flat work ironers of either the chest or cylinder type.

5 In accordance with the usual practice in the operation of these ironers, a plurality of cloth-covered rolls are journaled for rotation above a steam-heated drum or a chest, and the articles to be ironed are caused to be passed onward from one roll to the next by the use of a series of endless strings or tapes disposed transversely of the rolls.

In prior U. S. Patents Nos. 1,186,640 and 1,740,980 flexible stripper fingers are disclosed as 15 associated with the rolls for stripping the work therefrom, in lieu of the strings or tapes heretofore utilized. Particularly in U. S. Patent #1,740,980, I have disclosed flexible guard means bearing upon the feed side of a roll for preventing 20 its lapped cover cloth from dropping down or backwardly; and in a copending application Serial No. 374,477, which issued July 19, 1932, as Patent No. 1,867,741 on which Reissue Patent #19,004 was granted November 21, 1933, I have disclosed 25 guide toes to engage with the work and prevent the same from rising beyond a predetermined height and serving as well to assist in carrying the work toward the next succeeding roll.

The present invention has for its object the 30 provision of a novel and simple form of stripper member, and to consolidate in a single element the various features of stripping and guiding and guiding and guarding disclosed in the aforesaid patents and application for patent.

35 A further object resides in the arrangement of a "break-away" portion in connection with the stripper member.

Another object of the invention is to provide a 40 more efficient stripper finger and one which will readily fold or bend over when encountering an abnormal obstruction and thus avoid becoming enmeshed with work passing through the ironing machine. The design of this finger is such, also, that it will immediately return to its active position when released.

A further object of the invention resides in the 45 provision of a novel mounting element for the stripper member whereby the same may be readily applied and adjusted to the proper position with respect to the roll surface, and as readily removed when replacement is required.

The invention has for a still further object the 50 provision of means for supporting the stripper mounting element in a manner such that the said element with attached stripper member may be

swung above the ironing rolls for inspection and adjustment; and, also, in the provision of means for adjusting the said mounting element both vertically and angularly with reference to the 5 rolls.

In the accompanying drawings which illustrate the invention,

Fig. 1 is a fragmentary transverse section through a succession of ironing rolls and associated steam chests, and illustrates the application of the stripper members thereto and the mounting of the same upon the ironing machine. 10

Fig. 2 is a fragmentary plan of one end of the ironing machine equipped with the novel stripper members.

Fig. 3 is an enlarged transverse section taken on the line 3—3, Fig. 2 and looking in the direction of the arrows.

Fig. 4 is a transverse section taken on the line 4—4, Fig. 3 of the drawings.

Fig. 5 is a perspective view of the novel stripper member.

Fig. 6 is a perspective view of a combined stripper member and guide member which may be utilized in the ironing machine.

Fig. 7 is a perspective view illustrating a combined guide and guard member which may be utilized in the ironing machine.

Referring to the drawings, more particularly Figs. 1 and 2 thereof, 10 designates one of a plurality of rotatable ironing rolls such as are utilized in an ironing machine, for example, of the chest type, a said roll being journaled for rotation above a steam-heated chest 11 and the surface of which immediately beneath the roll is 35 generally concave to secure greater ironing contact.

A cover cloth 12, usually hair padding, wool padding, or matted padding, is frictionally held thereon in overlapping relationship to insure 40 retention of the cover on the roll surface.

Provision is made for mounting suitable stripper elements 15, more particularly illustrated in Fig. 5 of the drawings, to bear upon the delivery side of a roll to strip from the surface thereof work immediately as it emerges from between a roll and chest. In accordance with the invention, a stripper member embodies a vertically disposed strip 16 of spring steel to which is hinged approximately mid-way of its length a 50 further strip of spring steel 17. The latter has its lower end portion extending downwardly beyond the end of strip 16 and is bent also at an angle thereto to constitute the stripper element or finger 15 which is designed to engage the 55

surface of a roll. By thus projecting backwardly the stripper element 15 from the strip 16, a section constituted by the angular portion is adapted to guide or "break-away" the work toward the next roll, and to this end it is designed preferably to be arcuate and substantially parallel to the periphery of the associated steam chest.

The material of the member 17 is of much lighter gauge than that of the strip 16 so that it will readily yield with respect to the said strip, the same acting as an abutment for said strip of material 17. The material of the latter strip 17 is sufficiently light, also, to permit of its bending upwardly under jamming conditions, for example, as indicated in the dotted line position, Fig. 1; and provision is made, furthermore, for permitting also the strip 16 to swing outwardly, as is further indicated by the dotted line position, about a pivotal point at the top of the machine.

To this end, the upper portion of strip 16 is provided with the semi-circular bend 18 and straight-away top portion 19 and returned tongue 20 directed downwardly and inwardly toward the strip 16. This upper triangular end of the strip 16 thus formed is designed to be fitted over a suitable hollow holding bar 25 also of triangular shape, the top contacting with the top or one side of the triangular holding bar, while the tongue 20 contacts with its base and is arranged to be firmly held therein. For example, it may fit into a plurality of openings 26 formed in the base by slitting the same and pressing outwardly the slotted portion 27. By this means, the tongue may be readily inserted and substantially locked in position and also withdrawn when it is necessary to replace a stripper member, the stripper member as a whole hinging about the retained tongue portion to accommodate the outward motion of strip 16 when the end 15 meets with an obstruction. As soon as an obstruction clears, however, the element 17 with its end 15 will be returned to normal position under its own resiliency and the resiliency of the strip 16 to which the strip portion 17 is pivoted.

It is desirable to so mount the holding bars 25, which are disposed longitudinally of the rolls above the same and on the delivery side, that the entire stripper mechanism may be swung upwardly into position for examination and replacement, if necessary, of the stripper members.

This may conveniently be effected by carrying a holding bar 25 upon a pair of arms 30 extending along opposite sides of the ironing machine, the one end of an arm 30 being pivoted as at 31 to a suitable supporting bracket 32 which is adjustably secured to an upstanding stud 33. Bracket 32 is provided also with an upstanding lip 34, and the bar with a pivoted catch 35 to cooperate with the upper edge of lip 34 when said bar is swung upwardly and tilted slightly backwardly, as indicated in the dotted line position, Fig. 1. This will serve to hold an arm 30 securely in position while changes are being made to the stripper members carried by the holding bar.

The latter is arranged to be journaled in the outer ends of a pair of arms 36; and the said bar at its far end carries also an adjustable screw 37 to bear at its lower end 38 against the top of the next succeeding stud 33 for limiting the extent of downward movement of the arm 36 and to adjust thereby its vertical position and that of the bar 25 with reference to a roll 10.

It is further desirable that holding bar 25 it-

self be adjustable angularly, that is to say, about its journals, and to this end there is attached to the ends of the said bar a supplementary or secondary arm 40 movable therewith and having its outer end swivelled to the lower end 41 of a screw 42 which is adjustably mounted in a bracket 43 attached to arm 30. By this expedient, the holding bar 25 may be rocked more or less to provide the desired adjustment angularly in setting the stripping element end 15 with reference to the roll surface upon which it is to bear.

It is desirable, also, to mount on this holding bar 25 and between stripping elements a guide member, for example, of the nature set forth in Fig. 6. This guide member, similarly to the construction of the stripper member, is provided with a bend 45, straight-away top portion 46 and tongue 47 for mounting the guide member on the holding bar. At its lower end it is curved outwardly to afford an arcuate extension 48 which may be reinforced by returning the strip composing the guide member to the upright portion 49 and riveting the same thereto as at 50. Portion 49 may have attached thereto, also, a stripping element 51, so that a combined stripping and guide member may be had which is to be mounted at suitable intervals along a holding bar 25 therefor.

Or, if desired, there may be attached also to this guide member, reference being had to Fig. 7 of the drawings, an arcuate guard piece 52 for bearing upon the feed side of the succeeding roll. Thus, a very satisfactory and simple combined guide and guard member is provided which, similarly to the stripper member, may readily be mounted upon the holding bar and is readily removed in case replacement be required.

I claim:

1. A resilient narrow stripper member for use in a flat work ironer including ironing rolls, comprising a strip of spring metal bent over at its upper end to be removably secured to a support of the ironer, and a further strip of spring metal secured at its upper end to an intermediate portion of the first-named strip, being backed for a portion of its length by the lower portion of said first-named strip and having its free end directed downwardly and away from the lower end of said first-named strip to bear along its front edge on a roll.

2. A resilient narrow stripper member for use in a flat work ironer including ironing rolls, comprising a strip of spring metal adapted for attachment at its upper end to the ironer, and a further strip of spring metal of greater resiliency than the first-named strip and secured at its upper end to an intermediate portion of said first-named strip, being backed for a portion of its length by the lower portion of said first-named strip and having its free end directed downwardly and away from the lower end of said first-named strip to bear along its front edge on a roll.

3. A combined guide and stripper member for use in a flat work ironer which includes ironing rolls, comprising a strip of spring metal with upright portion adapted for attachment at its upper end to the ironer, the lower end being bent forwardly, then upwardly and backwardly and attached to the upright portion, and a stripper finger secured at its upper end to an intermediate point of the upright portion and extending outwardly from the upright portion of the strip of spring metal in a direction opposite to the forwardly bent portion to form a substantially continuous surface therewith.

4. A combined arcuate guide and arcuate guard member for use in a flat work ironer including a succession of ironing rolls with lapped cover cloth, comprising a strip of resilient spring metal having an upright portion adapted for attachment at its upper end to the ironer, the lower end being bent forwardly, then upwardly and backwardly and attached to the upright portion, and an arcuate guard member secured at its lower end 10 to the upwardly bent portion of the strip to embrace the feed side of a roll.
5. In a flat work ironer including a frame, ironing rolls mounted therein and stripper members associated with the rolls for stripping work therefrom: a holding bar for the said stripper members, a pair of arms pivotally connected to the frame at opposite ends of a roll and extending transversely to the axis thereof, means at the free ends of the arms to journal the opposite ends 20 of said bar therein, a secondary arm secured to the bar, and an adjustable screw carried by one of the pivoted arms and swivelled to the free end of the secondary arm whereby the same may be rocked to displace angularly the said bar.
- 25 6. In a flat work ironer including a frame and ironing rolls rotatably mounted therein: stripper members adapted to bear upon the surface of a roll, and means to mount the stripper members comprising a holding bar extending longitudinally above said roll, a pair of substantially horizontally disposed arms pivotally connected to the frame at the opposite ends of said roll and extending transversely to the axis thereof, means 30 at the free ends of the arms to journal the opposite ends of said bar therein, an upstanding stud on the frame, an adjustable screw at the free

end of one of the arms cooperating with the stud to limit downward movement thereof, a secondary arm secured to the bar, and a second adjustable screw carried by the said screw-bearing arm and swivelled to the free end of the secondary arm whereby the same may be rocked to displace angularly the said bar. 5

7. A member for stripping material from a roll, comprising a strip of spring metal adapted for attachment at its upper end to a support, and a further strip of spring metal secured at its upper end to an intermediate portion of the first-named strip, being backed for a portion of its length by the lower portion of said first-named strip and having its free end directed downwardly and away from the lower end of said first-named strip to bear along its front edge upon the surface of the roll. 10 15

8. In a flat work ironer including a frame, a steam chest mounted thereon, and a plurality of laterally disposed, clothed ironing rolls rotatably mounted in the frame above the steam chest, a plurality of resilient stripper members associated with the surface of a roll to strip goods therefrom, each member having an arcuate guide portion projecting on the delivery side of said roll substantially parallel and close to the surface of the associated steam chest and substantially across the entire space between said roll and the next roll, said arcuate guide portion affording a continuous unbroken surface with the stripper portion, whereby the goods are prevented from rising unduly and are directed to the nip of the next succeeding roll. 20 25 30

CHARLES EDWIN HAMILTON, SR.
